UNITED STATES PATENT OFFICE.

JAMES W. SCHMIED, OF WEST ORANGE, NEW JERSEY, ASSIGNOR TO WESTERN ELECTRIC COMPANY, INCORPORATED, OF NEW YORK, N. Y., A CORPORATION OF NEW YORK.

MODULATING CARRIER WAVES.

Application filed August 26, 1922. Serial No. 584,412.

To all whom it may concern:

Be it known that I, JAMES W. SCHMIED, a citizen of the United States of America, residing at West Orange, in the county of Essex and State of New Jersey, have invented 5 certain new and useful Improvements in Modulating Carrier Waves, of which the following is a full, clear, concise, and exact description.

10 This invention relates to systems for, and methods of, modulating carrier waves in accordance with signals and more particularly to "constant current" and "constant voltage" modulation systems for use in radio 15 telephony.

One object of the invention is to simplify systems of the type which produce and transmit modulated waves from which the unmodulated component has been wholly or 20 partly suppressed.

Another object is to increase the high frequency voltage which is impressed upon the transmitting circuit without utilizing a correspondingly increased voltage of the space 25 current supply source of a vacuum tube system which produces the waves to be transmitted.

The invention is herein illustrated in systems in which two vacuum tube oscillators 30 are connected to a tuned frequency determining antenna. The oscillators are so related to the antenna that the high frequency voltages produced by the oscillators will be impressed in series upon the antenna circuit.

35 Each oscillator has an output circuit coupled to the antenna and a feed-back coupling from the antenna to the input circuit. The electrode circuits of the oscillator tubes are connected to the antenna in opposing relation, that is, the circuits of one tube are connected oppositely with respect to the circuits of the other tube. The antenna is insulated from the vacuum tube circuits except for the usual ground connection. Other tubes 40

45 are provided of which the impedance is varied in accordance with signaling or waves in order to modulate the high frequency oscillations produced by the oscillation generating tubes. In the "constant current" circuit, the variable impedance tubes and the

tubes of the generators may have their cathodes connected to a common point and grounded. In the constant voltage type of circuit, the cathodes of the oscillator tubes and of the variable impedance tubes cannot 55 both be grounded by connections conductive to direct or speech frequency currents. It is preferred to ground the oscillator cathodes as shown.

"Constant current" and "constant voltage" 60 systems are known. See the article by R. A. Heising in the Proceedings of the I. R. E. August, 1921.

In the drawing, Fig. 1 is a circuit diagram 65 of a constant voltage modulating system embodying the invention and Fig. 2 is a circuit diagram of a constant current or shunt modulating system.

In Fig. 1, each vacuum tube 1 and 2 has 70 associated with it an output or plate circuit extending from the anode through a condenser 3, a coil 4, and the common condenser 5. The plate circuits are coupled to the antenna circuit 6 by means of the coupling 75 between the coils 4 and the fixed and movable coils 7 and 8, respectively. The fixed coils 9, and the movable coils 8, are also coupled to coils 10 in the grid or input circuits of the 80 vacuum tubes. Stopping condensers 11 in each input circuit and the usual high resistances 12 are provided. The source 13 supplies space or anode-cathode current to the tubes 1 and 2. Switches 14 are provided so that space current may, if desired, be supplied through a speech frequency choke coil 85 15. The purpose of the coil 15 is to make the suppression of the unmodulated carrier component more complete. In series with the tube 1 is the anode-cathode path of the tube 21 and in series with the tube 2 is the anode-cathode path of the tube 22. High frequency choke coils 23, of low impedance to speech frequencies, prevent the high frequency waves, generated by the oscillators, 90 from being dissipated in the tubes 21 and 22 and their associated circuits. Incoming waves from a microphone circuit or telephone line 24 are impressed upon the input or grid-filament circuits of tubes 21 and 22. 95 In each grid circuit is included a portion of 100

a resistance 25 or any other suitable impedance. The resistance 25 is divided into two approximately equal parts, one of which is included in each grid-filament circuit.

During operation the impedance of the tubes 21 and 22 will be varied by signaling waves in opposite ways, that is, when one tube is made of higher impedance, the other is made of lower impedance. The space current supplied to each oscillator tube will vary at a speech frequency rate. Consequently when one tube, for example, tube 1 is generating waves of higher than average amplitude, the tube 2 will be generating waves of lower than average amplitude. When no signaling waves are being applied to the input circuits of the modulating tubes the amplitude of the high frequency waves in the antenna will be small or zero because the oscillators are connected to the antenna in opposing relation. The input and output circuits of the two oscillator tubes are equally coupled to the antenna circuit. The two systems of coils 7, 8, 9 are alike and the coils 8 are to be adjusted to approximately the same position for a given wave length.

In Fig. 2, the antenna circuit is indicated as having two high frequency coils 26 in series. The plate and grid circuit coils 4 and 10 of each oscillator are coupled to one of the coils 26. The coils 4 and 10 are preferably variable both as to number of turns and as to their position with respect to coils 26. Coil 26 may also have a variable number of turns if desired. The coupling coil arrangements of Figs. 1 and 2 are interchangeable. The remaining elements of the high frequency oscillators bear reference numerals corresponding to the elements of Fig. 1 and function in a similar manner.

The modulating system in Fig. 2 is of the constant current type, that is, a source 13 supplies current through a speech frequency choke coil 27 to the oscillating tube 1 and the cooperating modulating tube 21 in parallel. Coil 27 has such high inductive reactance at speech frequencies that practically constant current is supplied through it. A similar coil 27 is connected in circuit with the oscillating tube 2 and its cooperating modulating tube 22. The tubes 2 and 22 consequently constitute a second constant current modulating system connected to the antenna circuit in opposed relation to that constituted by tubes 1 and 21. The elements 24 and 25 function to vary the impedances of the tubes 2 and 21 as is described in connection with Fig. 1.

For each tube 1, 2, 21, 22 may be substituted a plurality of tubes in parallel relation.

In the operation of the system of Fig. 2 as well as that of Fig. 1, the high frequency waves produced by each oscillator are impressed upon the antenna circuit in series,

approximately 180° out-of-phase with each other.

Although described in connection with radio systems the principles of the invention are applicable in systems for signaling or otherwise transmitting energy over line wire systems. A simple manner of adapting the systems illustrated to a line wire system is to substitute a condenser for the radiating capacity of the antenna circuit, thereby converting the antenna circuit into a closed tuned circuit, and coupling the transmission line to the closed tuned circuit thus formed.

Having described two systems embodying the invention, the features inherent therein which are believed to be novel are defined in the appended claims.

What is claimed is:

1. A radio transmitting circuit consisting of two electrically symmetrical circuits, each comprising a modulator tube and an oscillator tube, a common signal frequency input source for said circuits, means for preventing the oscillation generator tube from being short circuited by the modulator tube of each circuit, and means for coupling the oscillator tubes to an antenna circuit.

2. A radio transmission system comprising two electrically symmetrical circuits, each comprising a modulator tube and a high frequency tube, a speech frequency circuit oppositely coupled to said modulator tubes to vary the impedance thereof, and means for coupling the high frequency tubes oppositely to an antenna circuit.

3. A modulating system comprising a plurality of constant current modulating systems each comprising a high frequency discharge device and a variable impedance discharge device, said variable impedance devices having a common low frequency input circuit and said high frequency devices being coupled to a common high frequency output circuit.

4. A modulating system comprising two electrically symmetrical constant current modulating systems, each comprising a variable impedance device and a carrier wave generating device in parallel with respect to a common source of current and a speech frequency choke coil; a common speech frequency input circuit oppositely connected to said variable impedance devices, and a common high frequency output circuit for the said carrier wave generating devices.

5. A modulating system comprising a source of current, means for maintaining a constant flow of current from said source, parallel paths having a common portion through said source, each of said paths including a high frequency discharge device and a low frequency discharge device, means for varying the impedance of said high frequency discharge device at a carrier frequency rate, and means for varying the im-

pedance of said low frequency discharge device at a modulating frequency rate.

6. An inductance coil having high impedance at speech frequencies, a source of current in series therewith, two paths in parallel with respect to said source and coil, each of said paths containing two discharge

devices, and means for varying the impedance of one device in each path at a high frequency and the other at a low frequency. 10

In witness whereof, I hereunto subscribe my name this 23rd day of August A. D., 1922.

JAMES W. SCHMIED.
